UNITED STATES PATENT OFFICE.

WALTHER VIELHABER, OF ALTOONA, PENNSYLVANIA.

SHAFT-COUPING.

SPECIFICATION forming part of Letters Patent No. 288,746, dated November 20, 1883.

Application filed July 30, 1883. (No model.)

To all whom it may concern:

Be it known that I, WALTHER VIELHABER, of Altoona, in the county of Blair and State of Pennsylvania, have invented certain new and useful Improvements in Shaft-Couplings, of which the following is a specification.

This invention has reference to an improved shaft-coupling, which is especially designed for coupling shafts of smaller diameter in a simple, strong, and reliable manner; and the invention consists of an exterior cylindrical portion, and an interior spring-sleeve that is transversely split at about its middle, and provided with abutments at its ends, into which tapering screw-bolts or other suitable wedge-shaped pieces are inserted for spreading the abutments apart and securing the spring-sleeve tightly to the shafts to be coupled.

In the accompanying drawings, Figure 1 represents a vertical transverse section on line $x x$, Fig. 2, of my improved shaft-coupling. Fig. 2 shows an end view of the same, and Figs. 3 and 4 are vertical transverse sections of modified forms of my shaft-coupling.

Similar letters of reference indicate the corresponding parts.

Referring to the drawings, A represents the cylindrical exterior portion of my improved shaft-coupling, and B an interior spring-sleeve, which is either cast in one piece with the exterior cylinder or cast separately and attached to the same by a dovetail joint or otherwise, as shown, for instance, in Fig. 3.

The end of the sleeve B is provided with a shoulder or abutment, b , between which and an overlapping abutment, a , that is cast integral with the opposite end of the spring-sleeve B, or integral with the cylinder A, the tapering screw-bolts C are introduced. Either one or two bolts C may be used; or the wedge action on the ends of the spring-sleeve B may be produced by any other suitable means, which are introduced into the sockets formed by the abutments a and b .

The tapering screw-bolts C engage the threaded faces of the abutments a and b , and press the same thereby in opposite directions, whereby the spring-sleeve B is tightly applied around the ends of the shafts to be coupled, whereby they are firmly connected with each other.

The spring-sleeve B is split transversely at d , so that the two sections formed thereby respond independently of each other to the

pressure of the tightening screw-bolts. The exterior cylindrical portion, A, is extended at both ends beyond the spring-sleeve and the square heads of the screw-bolts, so as to avoid accidents, which are frequently caused by the projecting parts of shaft-couplings.

The spring-sleeve B is splined to the shafts, by means of a key, e , and groove, e' , at a point diametrically opposite, or nearly so, to the open ends of the spring-sleeve B, the thickness of which is correspondingly increased at that point, as shown at e' , Fig. 2.

By means of this coupling shafts of slightly different sizes can be connected, as each section of the spring-sleeve B can be tightened independently of the other, and one of the bolts C being screwed home a little more into its seat, so that the corresponding sleeve-section will hold a slightly smaller shaft.

With this shaft-coupling shafts can be connected in the following manner: The bolts C are loosened sufficiently to allow the coupling to slide upon one of the shafts. The other shaft is then placed in position so that the ends of the shafts are at or near the center of the coupling. The bolts C are then tightened and the splines driven into their seats at the ends of the shafts.

This coupling can be cheaply manufactured, as the only parts which require to be worked off are the interior surface of the spring-sleeve B and the sockets for the screw-bolts C, all other parts remaining as they come from the casting.

Having thus described my invention, I claim as new and desire to secure by Letters Patent—

In a shaft-coupling, the combination of an exterior cylindrical shell, an interior cylindrical spring-sleeve having a narrow longitudinal opening through the length of its shell, the shoulder b , the overlapping abutment a , the screw-bolts C, the spline e , and groove e' , the said shell and sleeve being cast in one piece or attached by means of a dovetail joint, substantially as and for the purpose set forth.

In testimony that I claim the foregoing as my invention I have signed my name in presence of two subscribing witnesses.

WALTHER VIELHABER.
